Primary Examiner — Mary Ann Calabrese*Assistant Examiner* — Katalin G Kloberg(74) *Attorney, Agent, or Firm* — Muncy, Geissler, Olds & Lowe, P.C.(57) **CLAIM**

The ornamental design for a table base, as shown and described.

DESCRIPTION

FIG. 1 is a perspective view of a table base, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a perspective view of a table base, shown within an environment of use.

The broken lines shown in the drawings illustrate environmental subject matter that form no part of the claimed design.

1 Claim, 7 Drawing Sheets(56)
